UNITED STATES PATENT OFFICE

149,896

DESIGN FOR A RAZOR AND SHEAR KIT

William E. Martin, Anaconda, Mont.

Application July 30, 1946, Serial No. 132,101

Term of patent 7 years

(Cl. D58—26)

To all whom it may concern:

Be it known that I, William E. Martin, a citizen of the United States, residing at Anaconda, in the county of Deer Lodge and State of Montana, have invented a new, original, and ornamental Design for a Razor and Shear Kit, of which the following is a specification, reference being had to the accompanying drawing, forming part thereof.

Figure 1 is a front elevational view of a razor and shear kit, showing my new design.

Figure 2 is a plan view.

Figure 3 is an end elevational view.

I claim:

The ornamental design for a razor and shear kit, as shown.

WILLIAM E. MARTIN.
